UNITED STATES PATENT OFFICE.

CHARLES L. WHITAKER AND NORMAN E. MIDDLETON, OF WAYNESBORO, PENNSYLVANIA, ASSIGNORS TO FRICK COMPANY, OF WAYNESBORO, PENNSYLVANIA, A CORPORATION OF PENNSYLVANIA.

AIR-AGITATING MEANS FOR ICE MACHINES.

Application filed March 10, 1926. Serial No. 93,702.

Our invention relates to improvements in air agitating system for ice plants for use with can grids and it is an object of the invention to provide means for introducing air 5 into the ice cans which can be positioned so as not to interfere with the removal of the ice or cans.

Referring to the accompanying drawings which are made a part hereof and on which 10 similar reference characters indicate similar parts,

Figure 1 is a top plan view of our invention, and

Figure 2, a detail view.

15 In said drawings reference character 10 indicates a can grid adapted to receive a plurality of cans 11 for containing water to be frozen. An air header 12 is disposed longitudinally of the grid adjacent the top of 20 the cans, the same being provided with nipples 13 to which pipes (not shown) for supplying air to the cans adjacent their bottom are connected by flexible connections 14 which are supported by brackets 15 of an ap- 25 proved type. An air supply pipe 16 is dis- posed adjacent the end of the grid and connected to air header 12 by a flexible connec- 30 tion 17. A valve 18 is provided for controlling the flow of the air from said supply pipe to said air header.

Said air header 12 is mounted on arms 19 which are pivoted or hinged on pins 20 in appropriate supports, whereby said air header may be swung from a position above 35 the tops of the cans to a position at one side of the grid, thereby permitting the ice to be removed from the cans for the purpose of harvesting. It will be understood, of course, when the air header 12 is swung over outside 40 of the grid as indicated by dotted lines in Fig. 2, the flexible connections 14 are disconnected from the tubes in bracket 15, so that the brackets 15 may be readily removed before the ice is dumped from the cans. The 45 arms 19 are preferably formed with intermediate angles to form a flat rest section 25 to accord a firm rest on the edge of the grid when swung to the outside position.

It will be obvious that various modifications in the details of construction may be 50 made without departing from the scope of our invention, which is defined in the appended claims.

Having thus fully described our said invention, what we claim as new and desire to 55 secure by Letters Patent, is:

1. The combination in an ice plant of ice cans, a frame for containing the cans, arms pivotally mounted at or near the side of the frame to swing into and out of position over 60 said cans, and an air supply header supported by said arms, substantially as set forth.

2. A can grid for ice making plants comprising a frame, ice cans in said frame, an 65 air supply adjacent the frame, an air header having communication with the air supply and pivotally supported on said frame, nor- mally overlying the cans but adapted to swing to a position outside the cans, sub- 70 stantially as set forth.

3. The combination in an ice plant, of ice cans, a frame for supporting the cans, arms pivoted on the frame in spaced relation and swingable into and out of position over the 75 cans, an air supply header carried by said arms and having connections for supplying air to the cans, a source of air supply adja- cent one end of the pivoted air supply 80 header, and a connection between the source of air supply and said header, substantially as set forth.

4. The combination in an ice plant, of ice cans, a frame for supporting the cans, arms pivoted on the frame in spaced relation and 85 swingable into and out of position over the cans, an air supply header supported by said arms and having connections for supplying air to the cans, a source of air supply adja- cent one end of the pivoted air supply 90 header, a connection between the source of air supply and said header, and a valve in said connection, substantially as set forth.

5. Ice making apparatus comprising a 95 frame for supporting ice cans, a header for supplying air to said cans, said header being

pivottally mounted and supported by said frame, substantially as set forth.

6. Ice making apparatus comprising a frame for supporting ice cans, an air header for supplying air to said cans, and pivottally mounted brackets supporting said air header, substantially as set forth.

7. Ice making apparatus comprising a frame, an ice can supported in said frame, a tube for supplying air to said can, an air

header, a connection between said tube and said air header, and a pivottally mounted bracket supporting said header, substantially as set forth.

In witness whereof, we have hereunto set 15
our hands at Waynesboro, Pennsylvania, this
4th day of March, A. D. nineteen hundred
and twenty-six.

CHARLES L. WHITAKER.
NORMAN E. MIDDLETON.
